UNITED STATES PATENT OFFICE.

ROBERT S. CADE, OF CANTON, OHIO, ASSIGNOR OF ONE-HALF TO ALONZO E. JACKSON,
OF CANTON, OHIO.

SHOE-REPAIRING MACHINE.

1,103,347.

Specification of Letters Patent. Patented July 14, 1914.

Application filed October 18, 1913. Serial No. 795,839.

To all whom it may concern:

Be it known that I, ROBERT S. CADE, a citizen of the United States, residing at Canton, in the county of Stark and State of Ohio, have invented a new and useful Shoe-Repairing Machine, of which the following is a specification.

My invention relates to improvements in shoe repairing machines, more especially designed to repair the heels of shoes and the objects are, first to provide means whereby the layers or lifts of the heels which have become worn can be removed; second, to so remove the worn layers that no injury will be caused to the remaining layers or lifts of the heels and to which remaining layers or lifts the new layers or lifts are to be attached; and third, to provide means for cutting the exposed portions of the nails after the worn layers or lifts have been removed. These objects, together with other objects, readily apparent to those skilled in the art, I attain by the construction illustrated in the accompanying drawings, although my invention may be embodied in a variety of other mechanical forms, the construction illustrated being chosen by way of example.

In the accompanying drawing Figure 1 is a perspective view. Fig. 2 is a perspective view of the top or upper portion of the machine and illustrating the positions of the shoes when placed upon the machine to be acted upon. Fig. 3 is a vertical section. Fig. 4 is a transverse section on line 4—4, Fig. 1.

Throughout the several views similar reference numerals indicate similar parts.

More specifically describing the construction of my improved shoe repairing machine the numeral 1 indicates a base or support, which may be of such a size that the machine can be moved from place to place or in other words to provide a portable machine. This support or base should be of such a size that the machine proper will be held in an upright position when in use. However if desired the machine can be attached to the floor of a room in practically the same manner that it is attached to the portable base. It will be understood that when the machine is to be attached to the floor of a room it is to remain practically permanent where placed.

To the plate 2 or the base 1 if desired are securely attached in any convenient and

well known manner the two parallel angle bars 3, which angle bars are formed of a length to constitute a machine of sufficient height to be conveniently operated. For the purpose of providing what might be termed a rest or anvil portion, the upper parts of the angle bars 3 are bent at right angles to the upper portions, the webs of the angle bars having been previously notched so that when the rest or anvil portions 4 are brought at practically right angles a miter joint is produced as to the webs of the angle bars. For the purpose of holding the rest or anvil portions in a rigid condition with reference to each other, the angle plate 5 is provided and is connected to the ends of the right angled portions 4. Between the angle bars or uprights 3 is located the reciprocating or sliding bar 6, which extends downward to a point about midway between the top and bottom ends of the angle bars 3. The bottom or lower end of the bar 6 is provided with the right angled portion or bar 7, which is extended beyond the edges of the webs of the angle bars 3, to which arm are attached the links 8; the bottom or lower ends of which are pivotally attached the operating foot-lever 9, which lever extends rearward and between the angle bars 3, and is pivotally connected to the bracket 10, which bracket may be of the form shown or it may be of any other desired form as the only object desired is to pivotally connect the lever 9, so that the same can be operated by the foot. The top or upper end of the bar 6 is provided with the neck or curved portion 11, which neck or curved portion is for the purpose of providing suitable means for properly arranging the heel layer or lift removing blade 12.

To the neck portion 11 and to the bar 6 are attached the L-shaped plates 13, to which L-shaped plates 13 is attached the blade 12 by means of suitable bolts or rivets 14. For the purpose of properly guiding the bar 6 at its top or upper end and causing the same to move up and down in true alignment, the plate 15 and the block or bar 16 are provided, the plate 15 is attached to the angled bars 3 and the block 16 is attached to the webs 17, said webs being directly under the rest or anvil portions 4. In order that the rest or anvil 4 may be properly braced so there can be no sagging or spring-

ing during the time that the layers or lifts of shoe heels are being removed, the braces 18 are provided, which braces are connected substantially as shown in the drawings, or 5 they may be differently connected, owing to the fact that the arrangement of the braces and the manner of connecting the same is simply mechanical. For the purpose of normally holding the bar 6, together with the 10 different parts carried thereby in its uppermost position the spring 19 is provided, the top or upper end of which is connected to some fixed part of the anvil and the lower end is connected to the top or upper ends of 15 the links 8, by which arrangement, said spring will automatically move the bar 6 upward carrying with it the free or outer end of the foot lever 9.

It is well understood that when a chisel 20 is driven between the layers or lifts of the shoe by a hammer the jarring or the blows given to the chisel have a tendency to loosen the layers or lifts designed to remain upon the heel and thereby injure the unworn portion 25 of the heel of a shoe. It is also well understood that the wedge action of the removing blade should be entirely in the direction of the lifts or layers designed to be removed and in order to provide for this one 30 sided or one direction wedge action I form one edge of the blade 12 substantially straight as best illustrated in Fig. 3.

It will be understood that in use the blade 12 becomes worn and in order to keep the 35 same in proper working order the same should be ground from time to time, thereby changing the original shape of the blade. In order to compensate for any change in 40 the shape of the blade by reason of its wear, the plates 13 are pivotally connected to the neck portion 11 by means of the bolt or rivet 20 and extend horizontally rearward and their rear ends are connected to the bar 6 by means of the bolt or rivet 21, which 45 bolt or rivet is located through the short elongated slot 22 by means of which the rear ends of the plates 13 can be adjusted up or down, thereby adjusting the vertical portions 50 of the plates 13 and the blade 12 at any desired angle to true vertical line, thereby 55 providing means for originally adjusting the blade 12 so that it will move up and down in a true vertical line and at the same time provide means for proper adjustment from time to time by reason of any wear that may take place, either from the use of the machine or from the grinding of the blade 12.

It is well understood that the lifts or layers 60 of the heels or bases are held to the shoe proper and are held together by means of suitably formed nails, portions of which 65 nail will be exposed after the worn lifts or layers have been removed and hence it is necessary to provide means for cutting the

exposed nails so that a smooth and even surface will be provided upon which the new layers of the heels may be placed.

In order to provide for the cutting of the exposed nails I provide the cutting blades 70 23 and 24, the cutting blade 23 being attached to the top or upper ends of the angle bars 3 and the cutting blade 24 being attached to the bar 6 so that, after the worn portion of the heel has been removed, the 75 heel is placed in the position illustrated in dotted lines Fig. 2 and the bar 6 brought down whereby the blades 23 and 24 are brought into cutting action with reference to each other. It will, however, be understood 80 that the lifts or layers of the heels must first be removed, which is done by bringing the blade 12 down and entering the same between the layer designed to remain on the heel and the remaining layers to be removed. It will, also, be understood that in use 85 it is immaterial as to how many layers are removed at a time; for instance if it is desired to remove three layers they may all be removed by placing the heel in such a position 90 that the blade will enter between the proper layers to remove the ones desired to be removed or a single layer may be removed at a time, it being a question of judgment as to how many layers are to be removed by one operation. What I have reference to by one operation is that the blade 95 is brought between the same layers any desired number of times to properly remove the same, regardless as to whether or not one or more layers are to be removed. For the purpose of limiting the upward movement of the bar 6 the stop plate 25 is provided, which stop plate is so arranged that the arm 7 will strike the bottom 100 or lower edge of said stop plate, thereby stopping the upward movement of the bar 6 together with the plates carried thereby at the proper point or place.

Having fully described my invention 110 what I claim as new and desire to secure by Letters Patent, is—

1. In a device of the character described, the combination of a base, an upright support secured thereto, an anvil located upon 115 the top or upper end of said support, a reciprocating bar adapted to be guided by the anvil support, said bar being provided with a neck portion at its top or upper end, L-shaped plates pivotally connected to said neck, a heel lift removing blade connected to said L-shaped plates, and means for reciprocating said bar.

2. In a device of the character described, the combination of a base, an upright support secured thereto, an anvil fixed to said support and located at the top or upper end thereof, a reciprocating bar guided by said support and provided with a neck portion at its top or upper end, L-shaped plates 120

pivots connected to said neck portion, a heel lift removing blade connected to said L-shaped plates, means for reciprocating said bar, and nail cutting blades, one of 5 said blades being fixed and the other one being movable with the reciprocating bar.

3. In a device of the character described, the combination of a base, a support secured to said base, a heel rest located at the top of 10 said support, a reciprocating bar, said reciprocating bar being arranged to be guided by the heel rest support, means for actuating said reciprocating bar, and a heel lift removing blade fixed to and carried by the 15 reciprocating bar, one edge of said blade being formed substantially straight and the other edge being beveled.

4. In a device of the character described, the combination of a base provided with a 20 bracket, a support connected to said base, said support consisting of angle bars spaced

from each other, an anvil located at the top or upper ends of said spaced angled bars, a reciprocating bar located between said spaced angle bars, a lever pivotally connected at 25 one end to said bracket secured to the base, links connected to said lever intermediate its ends and to the reciprocating bar respectively, a heel lift removing blade located at the top or upper end of the reciprocating 30 bar, and nail cutting blades, one being connected to said reciprocating bar and the other being connected to the top or upper end of the support.

In testimony that I claim the above, I 35 have hereunto subscribed my name in the presence of two witnesses.

ROBERT S. CADE.
